WILLIAM I. DAVIS, OF CAMPBELL, MISSOURI, ASSIGNOR, BY MESNE ASSIGNMENTS,
TO ESCO D. GRACE, OF POPLAR BLUFF, MISSOURI

INDIVIDUAL MAUSOLEUM

Application filed October 26, 1928. Serial No. 315,186.

This invention relates generally to mausoleums and, more particularly, to a certain new and useful improvement in mausoleums of individual type.

Mausoleums of the type stated are adapted to be partially embedded in the earth, and my invention has for its general object the provision of an individual mausoleum comprising a sealed casket-chamber and so constructed as to substantially or approximately retain said chamber free from moisture and dampness.

And with the above and other objects in view, my invention resides in the novel features of form, construction, arrangement, and combination of parts hereinafter described and pointed out in the claims.

In the accompanying drawings,

Figure 1 is a vertical longitudinal sectional view of an individual mausoleum embodying my invention, showing the lid or cover section in sealing relation over and upon the body portion in the provision of a dead air chamber above the casket-chamber;

Figure 2 is a horizontal section taken substantially on the line 2—2, Figure 1; and

Figure 3 is an enlarged fragmentary section on the line 3—3, Figure 2.

Referring now more in detail and by reference characters to the drawings, which illustrate a preferred embodiment of my invention, A designates the body-portion or shell of the mausoleum, which is of elongated rectangular or box shape, and which is cast or constructed from concrete or other suitable plastic material to include end walls 1, 1, side walls 2, 2, and a flat bottom wall 3, the shell A being open at its upper side. The material from which the shell A is cast or constructed is preferably treated in some suitable manner to render the walls substantially air and moisture proof.

In the formation of the shell or body A, its end and side walls 1 and 2 are provided upon their inner face with spaced shoulders 4 and 5, the former being disposed suitably adjacent the bottom wall 3 and the latter being disposed suitably adjacent the open top of the body A.

Rested upon the shoulder 4 and, in the for-

mation of the body A, sealed on the shoulder 4 and to the shell A by means of a layer of concrete or the like 6, is a horizontally disposed formed concrete or other suitable slab 7, which provides the floor of the casket-chamber *a* and the roof of a dead-air chamber *b* extending therebeneath throughout the entire area of the shell A.

Embedded, in the formation of body or shell A, to extend vertically in each of the end walls 1 and each of the side walls 2, are convection or air transfer tubes 8, the upper ends of which terminate above the plane of the upper internal shoulder 5, while the lower ends of which terminate below the plane of the lower internal shoulder 4. The tubes 8 are placed in said walls during the casting or formation of the shell A and function not only as so-called air and moisture transfer-tubes, but also both as reinforcements for the body walls 1 and 2, and as side air spaces or chambers between the casket chamber *a* and the exterior, each tube 8 being provided at its lower end with an L-extension 9 opening into the lower air chamber *b* and at its upper end with a similar extension 10 opening into the body A above the plane of the shoulder 5, as best seen in Figures 1 and 3. As will be observed, the open ends of the tube extensions 9 and 10 are flush with the inner surfaces of the body walls 1 and 2 and thus permit of ready removal of the inner form when casting the shell A.

As so constructed, the shell A is ready for use, and in use a casket B is suitably placed through the open top of the shell A to rest on the floor provided by the partition 7. A second formed slab 11 of concrete or other suitable material is now disposed horizontally within the shell A to rest on the upper shoulder 5. A layer of concrete or the like 12 is then suitably disposed over the slab 11, and the casket-chamber *a* hermetically sealed.

A moulded cover or lid 13 is provided for closing the upper open end of the body portion A, which lid or cover is preferably formed of concrete or other suitable plastic material preferably similar to that of the shell A. The lid 13 is of correspondingly rectangular shape in plan and preferably of

a dimension so that its marginal edges will extend somewhat beyond the outer surfaces of the body walls 1 and 2. The medial portion of the lid 13 is preferably made relatively thick for strengthening purposes, and at one end the lid 13 is provided with a projection 14 adapted to receive a suitable marker or name-plate 15. The lower surface of the lid 12 is preferably flat, save for an anchoring groove 16, which, when the lid 13 is in position upon the body A, is adapted to receive the upper margin of the body walls.

Prior now to closing the shell A, a layer 17 of a suitable soft plastic binder, such as cement or the like, is disposed upon the upper margin of the body walls, which, on hardening, the lid or cover 13 being suitably placed upon the body A, unites the cover 13 to the body and, at the same time, hermetically seals the air-space c defined in the shell A by the lid or cover C.

Thus the mausoleum includes a series of superposed chambers, namely, the intermediate casket-chamber a, the underlying lower air-chamber b, and the overlying upper air-chamber c, which upper and lower air-chambers function to protect the intermediate chamber from dampness and atmospheric changes, the intermediate chamber a being further protected in such regard by the side air-chambers provided by the tubes or flues 8.

Further, after the mausoleum is sealed up, it will be seen that the upper and lower chambers c and b will have communication through the series of tubes 8, any number of which convection or air transfer tubes 8 may be provided along each end and each side of the shell A; it is preferred, however, that at least two of such tubes be provided in each wall for properly retaining the form sections in position.

The mausoleum is intended to be embedded in the ground so that merely the lid 13 is exposed to the atmosphere. Due to such exposure, the air within the upper chamber c will be usually drier or at a higher temperature than in the lower chamber b; a thermic action will hence be created between the spaced chambers b and c, whereby moisture and dampness from the lower chamber b will be conveyed by convection through the tubes 8 to the upper air chamber c and be disposed of through the lid 13 by capillary action and atmospheric absorption.

Thus it will be apparent that I provide a unique construction for individual mausoleums, wherein the casket-chamber will be retained dry and free from moisture through the provision of protecting sealed air chambers arranged above and below the casket-chamber and having communication with one another in such manner as to eliminate through so-called capillary action and atmospheric absorption substantially all entering moisture, thereby more efficiently pre-

serving the interred casket and its contained corpse.

It is to be understood that changes in the form, construction, arrangement, and combination of the several parts of the mausoleum 70 may be made and substituted for those herein shown and described, without departing from the spirit of the invention or the scope of the following claims.

Having thus described my invention, what 75 I claim and desire to secure by Letters Patent is:

1. In an individual mausoleum, in combination, a box-shaped shell constructed as a unit of cementitious material and unitarily 80 comprising a base wall and upstanding side and end walls, upper and lower cementitious partition walls disposed horizontally within the shell in spaced relation to each other and to the upper margins of said side and end 85 walls and to the bottom wall and dividing the shell interiorly to include and provide an intermediate casket-chamber, a bottom air-chamber underlying the casket-chamber, and an upper chamber overlying the casket-chamber, a cementitious lid adapted for disposition upon the upper margins of the shell side and end walls and providing a roof for said overlying air-chamber, and pipe-members 90 embedded and concealed in certain of the up-standing walls of the shell and having outlets into said upper and lower air-chambers for 95 providing communication therebetween.

2. An individual mausoleum including a box-shaped shell constructed as a unit of cementitious material and unitarily comprising a bottom wall and upstanding side and end walls, a cementitious partition permanently fixed horizontally within the shell intermediate 100 said bottom wall and the upper margins 105 of said side and end walls, said partition forming the bottom wall of a casket-chamber and the upper wall of an air chamber underlying the casket-chamber, a second partition adapted to be fixed within, and to the side 110 and end walls of, the shell in spaced relation both from the upper margins of said walls and from the first partition and providing the upper wall of the casket-chamber, and a lid adapted to be sealed to the upper margins 115 of the side and end walls of the shell and providing with the second partition an air-chamber within the shell over the casket-chamber.

3. An individual mausoleum including a 120 box-shaped shell constructed as a unit of cementitious material and unitarily comprising a bottom wall and upstanding side and end walls, upper and lower horizontal cementitious partitions adapted to be marginally 125 sealed to and within the shell in spaced relation to each other and to the upper margins of said side and end walls and to the bottom wall and dividing the shell interiorly into a central casket-chamber, an air-chamber be- 130

tween the casket-chamber and the bottom wall of the shell, and an upper chamber overlying the casket-chamber, and a cementitious lid adapted for disposition and sealing upon the upper margins of the side and end walls of the shell and providing a closure for said overlying air-chamber.

4. An individual mausoleum including a box-shaped shell constructed as a unit of cementitious material and unitarily comprising a bottom wall and upstanding side and end walls, said side and end walls having interior shoulders spaced from each other and from the bottom wall and the upper margins of the shell, cementitious partitions disposed horizontally within the shell and resting for sealing upon the respective shoulders, and a lid adapted to be sealed to and upon the upper margins of the shell side and end walls, said partitions and lid dividing the shell into a central casket-chamber and closed air-chambers within the shell overlying and underlying the central casket-chamber.

5. An individual mausoleum including a box-shaped shell constructed as a unit of cementitious material and unitarily comprising a bottom wall and upstanding side and end walls, said side and end walls having interior shoulders spaced from each other and from the bottom wall and the upper margins of the shell, cementitious partitions disposed horizontally within the shell and resting for sealing upon the respective shoulders, a lid adapted to be sealed to and upon the upper margins of the shell side and end walls, said partitions and lid dividing the shell into a central casket-chamber and closed air-chambers within the shell overlying and underlying the central casket-chamber, and air passages in the walls of the shell affording communication between said upper and lower air-chambers.

In testimony whereof, I have signed my name to this specification.

WILLIAM I. DAVIS.

CERTIFICATE OF CORRECTION.

Patent No. 1,815,883.

Granted July 21, 1931, to

WILLIAM I. DAVIS.

It is hereby certified that the name of the assignee in the above numbered patent should have been written and printed as Esco D. Groce, instead of "Esco D. Grace", as shown by the records of assignments in this office; and that the said Letters Patent should be read with this correction therein that the same may conform to the record of the case in the Patent Office.

Signed and sealed this 3rd day of November, A. D. 1931.

(Seal)
